UNITED STATES PATENT OFFICE.

JEROME A. CROWLEY, OF RANDOLPH, NEW YORK.

DEVICE FOR TABULATING BONDS AND OTHER SECURITIES.

1,347,325.

Specification of Letters Patent. Patented July 20, 1920.

Application filed November 28, 1919. Serial No. 340,981.

To all whom it may concern:

Be it known that I, JEROME A. CROWLEY, a citizen of the United States, residing at the village of Randolph, in the county of 5 Cattaraugus and State of New York, have invented certain new and useful Improvements in Devices for Tabulating Bonds and other Securities, of which the following, taken in connection with the accompanying 10 drawings, is a specification.

The invention relates to tabulating devices for United States bonds and other securities which render accurate the keeping account of successive interest payments on 15 said bonds and securities, greatly reducing the work of the banks, loan companies and similar institutions handling Government loans and the like; and the invention consists in a tabulating card for the use of the 20 bank and a coupon or pass book having a contract therein which becomes operative by the issuance of said coupon book and is canceled by the surrender of the bonds and securities and the return of said coupon or 25 pass book, the said cards and coupon or pass book being arranged for different kinds of bonds or securities with special tabulating divisions for interest payments thereon; and the invention consists in the novel features 30 and combinations hereinafter set forth and claimed.

In the drawings, Figure 1 is a plan view of one side of the tabulating card; and Fig. 2 is a similar view of the opposite side of 35 said card showing the manner of tabulating the bonds or securities and the interest payments on the same. Fig. 3 is a plan view of the open coupon or pass book showing the manner of tabulating the bonds and securities 40 for the protection of the depositor and the interest payments on the same; and Fig. 4 is a perspective view of said coupon or pass book.

Like characters of reference refer to corresponding parts in the several views.

The numeral 10 designates the tabulating card upon which the name of the depositor of the bonds or securities is placed as shown in Fig. 1, and which is given the same number 50 as the pass book, which is designated by the numeral 11.

The card is divided into divisions 12, 13, 14, 15, 16 and 17 and as many more as may be necessary. The card shown is arranged 55 for the different United States bonds of the first, second, third, fourth and fifth Liberty

Loans, as shown by the listed entries in Figs. 1 and 3 for the depositor, John Smith, of Randolph, New York, as shown in division 12 of Fig. 1, the interest on said bonds 60 collected by the bank and dates thereof being entered in divisions 13, 14, 15, 16 and 17 according to the rates of interest upon the same.

The coupon or pass book 11 has corresponding entries therein tabulating the deposit of the bonds of the different loans and the interest payments upon these different bonds of said different loans, said coupon or pass book having a printed statement at the 70 top of each tabulation 19 of interest payments stating to which Liberty Loan the bond belongs upon which payments are made.

At the top of the page designated by the 75 numeral 18, upon which the bonds are tabulated, a printed statement acknowledging the receipt of the bonds is placed, stating that the receipt is subject to the conditions and regulations appearing therein. The 80 regulations are printed within the coupon or pass book and form a contract between the bank and the depositor and state for example that the bank will receive United 85 States bonds and other securities from its customers and other parties who desire to deposit them for safe keeping in its custody, but subject to the condition that said bank assumes no responsibility therewith, except that such bonds or other securities so deposited shall receive the same care as given 90 its own securities.

All bonds or other securities deposited with said bank shall be listed in a pass or coupon book issued by said bank and such 95 pass book shall be the receipt to the depositor and the acceptance of said pass book by the party depositing said bonds or other securities shall constitute an agreement on his or her part with said bank of the aforesaid conditions, and of the following regulations:

That said bank shall have the privilege to detach interest coupons attached to said bonds or other securities thus deposited with 105 said bank, to collect the amount thereof, and upon presentation of this pass or coupon book, the said bank will pay to the holder thereof the amount of said interest thus collected and enter the amount paid in this 110 pass or coupon book together with the date on which the interest was collected, which

entry shall constitute a receipt for said payment.

That said bank will not be called upon to make such interest payments without presentation of this pass or coupon book at its counter, and that the possession of this pass or coupon book and the presentation thereof shall be sufficient authority to said bank to make such interest payments.

10 That said bank will return said bonds or securities upon demand of the owner and holder of this book, or bonds or securities of like denomination of the same issue, and thereupon this pass or coupon book shall be 15 surrendered to said bank.

Great difficulty has been experienced by the different banks and other institutions in handling the different Liberty Loans for the convenience of depositors, the banks not receiving any remuneration therefrom. By the herein described system, the depositor is more completely protected than he could otherwise be, and at the same time the bank is empowered to detach the coupons and collect from the Government the amounts thereof, thereby holding a considerable fund in its possession which can be placed at interest to thereby cover the cost of furnishing protection to the depositors and for the 25 safe keeping of said bonds and securities.

I claim as new:

A bank tabulating device for bonds and

the like including a depositor's pass book having designated spaces to receive a list constituting acknowledgments by the bank 35 of receipts from the depositor of bonds of the different issues and of the interest borne by each issue, and having a series of divisions one for each of the different bonds so listed, each division having a designated 40 space to receive the amount of the bond and having a series of designated spaces to receive a record of the interest collected by the bank and placed to the credit of the depositor as of the date collected by the 45 bank, and a card for retention by the bank having designated spaces to receive a record list of the different bond issues held by the bank to the credit of the depositor and having a series of divisions one for each of 50 the different bond issues so listed, each of the last named divisions having designated spaces to receive the amount of the bond and further having a series of designated spaces to receive a record of the interest 55 collected by the bank and held thereby to the credit of the depositor as of the date collected by the bank.

In testimony whereof I have affixed my signature in the presence of two witnesses.

60 JEROME A. CROWLEY.
